UNITED STATES PATENT OFFICE.

JEAN BAPTISTE GABRIEL EMILE COIFFE, OF LIMOGES, FRANCE, ASSIGNOR
TO GUSTAVE VOGT, OF SAME PLACE.

DESIGN FOR A DISH.

SPECIFICATION forming part of Design No. 18,979, dated April 2, 1889.

Application filed February 15, 1889. Serial No. 300,051. Term of patent 7 years.

To all whom it may concern:

Be it known that I, JEAN BAPTISTE GABRIEL EMILE COIFFE, a resident of Limoges, Haute-Vienne, Republic of France, have invented 5 a certain new Design for Porcelain, Crockery, Earthenware, Faience, and Glass Dishes, of which the following is a specification.

Figure 1 is a top view of my newly-designed dish and its cover. Fig. 2 is a side view of the 10 same.

Similar letters of reference indicate corresponding parts.

The essential features of my design consist in an outwardly-projecting border at the top 15 of the dish, representations of shells at the corners of the border, and handles on those parts of the border on the ends of the dish.

A is the body of the dish; B, the raised border projecting outward at the upper edge of 20 the dish, the top opening of which is quadrilateral.

C are representations of upright shells at the corners of the border B. The border is slightly curved downward between the representations 25 of shells C. The handles E are on the outer edges of the end parts of the border, and con-

sist of the cross-pieces F and the end pieces, G, which are made flaring, the inner ends of the outer edges of said end pieces being at the offsets H at the sides of the representations 30 of shells.

The handle J on the cover K is like the dish-handles.

Having thus described my invention, I claim as new and desire to secure by Letters Patent— 35

The design for a dish herein shown and described, consisting of an outwardly-projecting border along the top edge of the dish, representations of shells at the corners of said border, and handles on the outer edges of those 40 parts of the border on the ends of the dish, the end pieces of said handles being flared from the ends of the handle cross-piece to the border, substantially as set forth.

In testimony that I claim the foregoing as my 45 invention I have signed my name in presence of two subscribing witnesses.

JEAN BAPTISTE GABRIEL EMILE COIFFE.
